SAFETY DOORLOCK

Application filed April 30, 1927. Serial No. 187,808.

The present invention pertains to improvements in the art of locks and the same refers more particularly to a combined permutation lock and latch mechanism. The aim of the present invention is to obviate the necessity of employing both a permutation lock and a latch for doors by combining these two mechanisms in a unitary structure employing but a single operable bolt which can be made to assume the character of a lock bolt or latch bolt by a single adjustment of the mechanism associated therewith. The invention therefore has as its main object the provision of a structure employing a single bolt which may be operated as a day latch, when it is not desired to lock the door, and which on the other hand can be employed as a permutation lock bolt by the simple adjustment of means which will be fully set forth in the following specification.

Another important object of the invention resides in a lock of the above character wherein the permutation mechanism thereof includes a ratchet member against the teeth of which a pawl engages and which will produce a clicking sound corresponding to the predetermined movement of the tumbler plate, with the end in view of providing annunciative means whereby the person operating the mechanism may determine at what moment he must reverse the movement of the tumbler plate in order to set the same in proper registry for permitting the retraction of the bolt.

Still another important object of this invention resides in the provision of a permutation lock wherein the bolt member cannot be retracted until the tumbler members have been brought to a predetermined position.

Referring to the following specification and claim other important objects and advantages of this invention will readily become apparent.

In the drawings:-

Figure 1 represents a plan view of the lock mechanism, the same being shown with the cover plate removed and disclosing the mechanism therein.

Figure 2 represents a longitudinal sectional

view of the lock structure taken on the right side of the bolt as shown in Figure 1.

Figures 3, 5 and 6 respectively illustrate plan views of the several tumbler plates.

Figure 4 represents a split washer in plan view employable between each of the tumbler plates. 55

Figure 7 is a plan view of the ratchet disk.

Figure 7a represents a perspective view of 60 the operating sleeve member.

Figure 8 represents a transverse sectional view taken on a line through Figure 1.

Figure 9 is a longitudinal sectional view taken on a line through Figure 1, on the opposite side of the bolt from which the sectional view in Figure 2 was taken. 65

Figure 10 is an enlarged perspective view of the pawl actuating means for retracting the bolt.

Figure 11 is a perspective view of a pawl trip means for converting the lock mechanism from its combination character to the knob operable latch, and 70

Figure 12 is a perspective view of the pawl member proper. 75

Referring to the drawings more in detail wherein like numerals designate like parts, a rectangular casing A is closed at one side and has secured to the inner side thereof an annular shell B'. A suitable face plate may be secured to one end of the casing A and has an opening therein registered with the bolt opening in the end of the casing through which the elongated bolt B is slidable. Spaced guide plates 1 arranged on the inner side of the side wall of the casing serve to guide the bolt in its rectilinear movement. The inner end of the bolt B is provided with a reduced extension 2. The reduced extension 2 is adapted for slidable movement through an opening in the annular wall B'. 80

The annular wall B' is formed with spaced circumferentially extending slots T2, U2, and V2, while an additional slot is formed in the annular shell between the last mentioned slot and the closed side of the casing A. A pawl 3 is provided at one end with a laterally disposed lug Z engageable through the last mentioned slot for the purpose herein-after more fully described. A post 4 is se- 85

90

95

100

cured to the side wall of the casing A and the opposite end of the pawl 3 is pivoted thereon. A spring Z' is engaged with the post 4 for tensionally maintaining the lug Z projected through the last mentioned slot in the annular shell.

A second post 5 is secured within the casing A and has a spring element 6 projecting therefrom and engaged with the bolt B for 10 tensionally maintaining the same projected.

An arm 7 projecting laterally from the bolt B is pivoted at its outer end within the bifurcated end of a bar W. A laterally disposed head W' at the opposite end of the bar 15 W is provided with teeth R', U' and V'. The head is also provided with an apertured formation 8 through which one end of the spring element 9 is slidable and adapted for tensionally maintaining the teeth projected through 20 the slots T2, U2 and V2. The spring element is convoluted about the post 4 and anchored to the casing A in the manner shown in Figure 1.

The mechanism includes a plurality of 25 tumbler plates and for the purpose of minimizing the description and operation thereof, they will be described immediately hereinafter in their registered relation, or in other words in a position permitting the re- 30 traction of the bolt B. The closed side of the casing is formed with an opening concentric with the annular wall B', and a bushing L is adapted to have one of its reduced ends engaged through said opening and to project 35 through the wall B. The bushing is formed with a polygonal bore and is provided with a radial rib O at its periphery.

A ratchet disk X is provided with a predetermined number of teeth around its periphery, a space Y being left between the teeth at one point on the periphery of an extent that would have been taken up by one of the teeth. The inner edge of the plate is formed with the notch Y' in which the rib O engages when the same is disposed within the shell B'. The lug Z of the pawl 3 is adapted to engage between the teeth of the ratchet disk X.

The tumbler plate E, shown in Figure 6 50 of the drawings has a centrally cut portion through which the sleeve L extends. The rib O of the sleeve is operable within an enlargement of this opening, which is designated by R. The plate is radially split to provide the space S2. An elongated peripheral indenture V is also formed in the tumbler plate. This plate is arranged within the annular shell over the ratchet disk X.

A second tumbler plate referred to by D 55 is formed with a central opening, the edge portion of which is indentured as designated by Q to accommodate the radial rib O. This plate is likewise split to provide the radial opening A, while the periphery is formed with an elongated indenture U. This

plate D is adapted to be arranged over the plate E.

A third tumbler plate C is formed with a central opening and a split P extends inwardly from the periphery to communicate with the central opening. The split S also communicates with the peripheral circumferentially extending indenture S', extending in one direction from the split P, while the peripheral portion of the plate is also formed with a notch T. This plate C is disposed over the plate D so that the radial rib O of the sleeve will project into the space S.

In Figure 4, a washer is shown designated by F and is split to provide the radial space S'. The periphery of this washer is provided with lugs F' engageable within longitudinally extending grooves in the inner face of the annular shell B'. One of these washers F is adapted to be interposed between each of the tumbler plates C, D and E. In arranging the tumbler plates to permit of the retraction of the bolt B, the plate E as well as the plates D and C are arranged with the radial openings S, S' and S2 in registering relation and in registry with the opening of the annular shell B' through which the reduced end 2 of the bolt is slidable. This disposition of the plates while causing the registering of the indentures T, U and V will nevertheless result in the irregular termination thereof in respect to each other. The teeth of the pivotal bar W shown in Figure 10 is adapted for engagement within the foregoing indentures. In this position of parts the lug Z is engaging within the space Y at the end thereof farther away from the notch Y' in which the radial rib O of the sleeve engages.

Obviously, by now rotating the sleeve L counterclockwise the shoulder provided by the notch T in the uppermost tumbler plate C will engage the uppermost tooth R' on the bar W. Due to the frictional relation of the washer between the tumbler plates, the plate C is the only plate rotated by the sleeve in this direction, the rib O being free to move within the indentures R and Q of the plates E and D, respectively. The movement of the plate D will thus cause the teeth to move toward the opposite end of the slot through which they project, the teeth U' and V' being free to move toward the opposite ends of the peripheral indentures V and U of the plates E and D, respectively. The consequential pull on the bar W will result in the retractile movement of the bolt B, its reduced end portion 2 moving into the radial openings of the tumbler plate. In this manner the mechanism may be employed for retracting the bolt after the tumbler plates have been previously set.

If now desired, the mechanism may be set so that the same can only be employed as a latch wherein the tumbler plates will rotate in unison and not individually.

5 An L-shaped bar 10 has one end portion *a* projecting through the face plate A', while its short leg end portion is disposed between the annular shell and the opposite end of the casing A. The end of the small leg portion is provided with an inwardly disposed foot *c* adapted for engagement behind the free end portion of the pawl 3. A pin *b* is likewise 70 slidable through an opening in the face plate 10 A' and has its inner extremity secured to one end of a rocker arm 11. This rocker arm is pivotally mounted on the post 5 while its opposite end is bifurcated for receiving an up-standing pin 12 on the L-shaped member 10. 15 A spring 13 extends from the post 5 and has its end bent for engagement in a pair of notches 14 on the inner edge of the L-shaped member 10.

20 When the L-shaped member has been forced inwardly to assume the position shown in Figure 1 of the drawing, the spring 13 is engaged in the outermost notch 14 for retaining the member in this position with its foot member *c* disengaged from the end portion 25 of the pivotal pawl 3.

In order to adjust the mechanism so that the same can only be operated as a latch, the pin *b* is moved inwardly, resulting in the outward movement of the L-shaped member 10 30 and the engagement of the foot *c* against the free end of the pivotal pawl 3, thus maintaining the lug Z engaged within the elongated indenture Y of the ratchet plate X. In this manner the ratchet plate can only 35 move to the extent of the indenture Y, which is sufficient to cause the retraction of the bolt B.

40 In employing this mechanism as a permutation lock the foot *c* is disengaged from the pawl 3 and the sleeve rotated in clockwise direction. This results in a confused relation of the tumbler plates and they can only be re-set by a person having knowledge of the proper combination of movements necessary 45 to return the plates to registry. The teeth on the ratchet plate X in contacting with the lug Z will produce a clicking sound announcing the disengagement of the lug from one tooth and its engagement with the next tooth. The teeth of the plate correspond 50 in number to the distance around the periphery of each tumbler plate from the ends of its peripheral indenture. By first rotating the ratchet plate X in a clockwise direction so that the lug Z is engaged within 55 the indenture Y, the mechanism is then in a starting position from which counts may be made of the clicking sounds made as the ratchet plate is then rotated in alternate directions to bring the radial openings S, S' and S₂, successively into registry with the opening through the annular shell through which the reduced end 2 of the bolt is 60 slideable. When the tumbler plates have moved 65 to a position with their radial openings in

registry both with respect to each other and to the opening in the annular casing, the teeth on the head of the bar W will be completely within the peripheral indentures of the plates and may thus be actuated by further rotation of the plates in a counterclockwise direction to engage notch T with tooth R' resulting in the retractile movement of the bolt as described above. 70

75 It is to be understood that this invention is not limited to any particular sized peripheral indentures, nor are the teeth on the ratchet disk X to be limited, as a variance in these features may be made to produce a greater or lesser number of combinations. 80

Having described the invention, what is claimed as new is:—

85 In a lock mechanism comprising, a casing, a bolt slideable through one wall thereof, movable members having registrable openings therein, said members being arranged at the inner end of said bolt, means for setting said members with their openings in registry, into which the inner end of the bolt may be retracted, and means operated by 90 said members whereby the bolt may be thus retracted, said means consisting of a bar pivotally connected to the bolt and provided with a pawl head, said members being formed with indentures into which the pawl 95 head engages when the openings of the members are in registry, whereby the movement of the members will result in the pulling of the bar and the consequential retraction of the bolt. 100

105 In testimony whereof I affix my signature.
